UNITED STATES PATENT OFFICE.

ALFRED MARCOTTE, OF GASTON, CALIFORNIA.

GOLD-SAVING APPARATUS.

SPECIFICATION forming part of Letters Patent No. 683,613, dated October 1, 1901.

Application filed April 24, 1901. Serial No. 57,257. (No model.)

To all whom it may concern:

Be it known that I, ALFRED MARCOTTE, a citizen of Canada, residing at Gaston, county of Nevada, State of California, have invented 5 an Improvement in Gold-Saving Apparatus; and I hereby declare the following to be a full, clear, and exact description of the same.

My invention relates to an apparatus which is designed for saving gold which is so fine 10 and light that it is carried along at or near the surface of the flowing pulp and water with which it is mixed.

My invention consists of a sluice, a supply tank or hopper with an automatically-operating gate, by which the material is periodically discharged into the sluice, a series of counterbalanced amalgamated or blanket-covered plates, and a means for suspending them between their ends so that the current 15 flowing beneath will contact with the lower surfaces of the plates and any gold carried thereby may be amalgamated or caught by the rough or blanket surfaces. The lower end of the sluice beyond these plates may have a 20 reservoir of quicksilver, through which the heavier material passes before escaping from the sluice and by which any remaining gold 25 will be caught and retained.

The invention also comprises details of construction, which will be more fully explained by reference to the accompanying drawings, in which—

Figure 1 is a longitudinal section through a sluice, showing the gold-saving device in 35 side elevation. Fig. 2 is a plan of one of the gold-saving plates. Fig. 3 is a front view of a suspending-rod and weight. Fig. 4 is a section of a portion of one of the plates, showing an under surface of fibrous or blanket 40 material.

A is a sluice having any desired length of inclination. Within this sluice are suspended my devices for saving gold. These devices consist of plates 2 3 4, which may be used 45 either separately, in series, or any number of them in conjunction, as may be desired. The plates may be made either entirely of metal or they may be made partly of metal and partly of wood. They may be made in single metal sheets, as at 2 and 3, or they may 50 be made in two or more parts, one of which is adjustable with relation to the other. These

plates are suspended by shafts, as 6, extending transversely across the sluice and passing through upturned lugs 7 upon the sides 55 of the plates, so that the plates are suspended with their lower surfaces a short distance above the bottom of the sluice. These lower surfaces are either silvered or amalgamated, as before stated, or in some cases they may be 60 covered with a rough fibrous or blanket material, as at 3', which will catch particles of gold, which may be rusted or otherwise in such condition that they will not amalgamate, but which can be detained by such surfaces. The plates are preferably suspended from points nearer the upper end, and the lower surfaces are curved, as shown, so that when the current passes beneath them the lower ends of the plates will be lifted and, as 65 it were, floated upon the surface of the water by reason of the current passing beneath them. In order to properly counterbalance these plates, I have shown weights, as at 8, with rods or connections 9, upon which they 70 are carried and upon which they may be adjusted to or from the fulcrum-rod from which the plates are suspended. This allows me to adjust the weight of the lower end of the plate with relation to the force of the current 75 flowing beneath, so that the pressure upon the surface of the water can be regulated, and the rubbing contact of the flowing pulp and particles of fine gold carried thereby will cause the gold to adhere to the silvered or amalgamated surface of the plate 80 or to be entangled in the fibers of the blanket or similar material with which the lower surfaces of the plates may be coated. In some cases it may be found convenient to adjust 85 the plates by fitting them to slide in the turned-over edges of another plate, which serves as a guide, as at 10. In this case the plate 4 may be moved backward or forward with relation to the suspending-shaft, the 90 lugs of which are carried upon the turned-over plate, and the adjustment may be made without the use of any supplemental weight, such as is shown at 8. If found desirable, it will be understood that as many of these 95 plates of either of the forms above described may be used in series and arranged with relation to each other to suit the character of the material which is flowing.

In some cases the material may be in the form of thin light scales, which will be carried upon the surface in such a manner that it would be easily entangled with and arrested by the blanket-surface. In either case the character of the gold may be such that it will easily amalgamate or be arrested by the silvered or amalgamated surfaces, and in some cases where the gold is what is known as "rusty" and it will not easily amalgamate the passage beneath a number of these surfaces and the rubbing contact therewith will sufficiently brighten the gold so that it will at least adhere. Some of the gold may be of sufficient weight to settle upon the bottom of the sluice, and I have therefore shown part or all the sluice, as may be desired, having the silvered or amalgamated plate, as at 11, fitted in the bottom, over which the pulp and water will pass, and in some portion of this plate is a sunken pocket or depression, as at 12, which serves to contain mercury, into which any particles of gold that may have hitherto escaped will pass and where it will be arrested and amalgamated.

As shown at 5, the plate may be made convex upon both sides. It may be of wood or other material, and upon one side is fixed a metal silvered or amalgamated plate and upon the other a blanket or other fibrous surface, so that a single plate can be employed by reversing, and in this construction the counterbalance-weight 8 is carried upon the rod or support 9, which may be pivoted in the sides of the block 5', there being several openings to allow it to be adjusted toward either end to regulate the pressure of the flow upon the surface of the pulp flowing beneath, as before described. In order to supply this sluice with the pulp and pass it through with a periodical flow, I have shown a hopper or receiver 13, having an open bottom and a hinged gate, as 14. This gate is normally held closed by a chain 15, which connects with one arm of a lever 16. This lever is suitably fulcrumed, as at 17, and upon the outer end of the lever is an adjustable weight 18, by which the gate is kept closed until the tank or receiver has been filled to any desired depth. The superior weight of the water and pulp upon the gate 14 will then open the latter and allow the contents to flow down the sluice. This flow may be maintained regularly, if desired, or the gate may be so constructed that it will open and allow a considerable rush of material to flow down the sluice. The flowing material will pass beneath the plates 2, 3, and 4, as previously described, and will thus cause any gold carried by it to contact with some one or more of the plates and eventually be arrested.

Having thus described my invention, what

I claim as new, and desire to secure by Letters Patent, is—

1. The combination with a sluice of a counterbalanced plate having a silvered or amalgamated lower surface, and means by which said plate is suspended between its opposite ends within the sluice so that the current flowing therethrough will lift and float the plate upon it.

2. The combination with a sluice, a means for supplying a current of pulp and water thereto, of one or more counterbalanced plates suspended between the ends so that the lower surface will impinge upon the current flowing beneath, said surface being adapted to catch and arrest particles of gold floating in the current.

3. The combination with a sluice and a means for supplying a current of pulp and water thereto, of a plurality of plates having adjustable counterbalances and pivotally suspended above the sluice so that the lower surfaces are lifted and rest upon the current flowing beneath said surface, said plates being convexed and adapted to arrest and hold particles of passing gold.

4. The combination with a sluice and means for supplying a current of pulp and water thereto, of one or more plates suspended by the sluice having the lower surfaces fixed and adapted to retain particles of gold flowing through the sluice, and adjustable counterbalance-weights by which the pressure of the plates upon the flowing current may be regulated.

5. An apparatus for the saving of gold, consisting of a sluice, a plurality of suspended convex-bottomed plates having surfaces adapted to retain particles of gold, adjustable counterbalances for the plates, and a plate having a quicksilver-containing depression over which the pulp is caused to flow after leaving the suspended plates.

6. An apparatus for the saving of gold consisting of a sluice, plates suspended above said sluice having the convex lower surfaces adapted to rest upon the current flowing beneath, adjustable counterbalances for the plates, and a means for supplying material to said sluice, consisting of a hopper or receiver having a gate in the lower part, a counterbalance-lever and connection with said gate, whereby the pressure of material in the receiver opens the gate by overcoming the weight of the counterbalance.

In witness whereof I have hereunto set my hand.

ALFRED MARCOTTE.
